Application November 18, 1944, Serial No. 564,148

12 Claims. (Cl. 271—56)

1

This invention relates to sheet feeders, and more particularly to sheet calipering or excess sheet detecting mechanisms thereof employed to prevent a sheet feeder from feeding more than one sheet at a time to a printing press or other machine.

The present invention while capable of use in sheet by sheet feeders is particularly adapted for embodiment in stream feeders, or in combination stream and sheet by sheet feeders, wherein the sheets are advanced in lapped relation or singly one after another from a pile or supply to a printing press or other instrumentality with which the feeder is associated.

One object of the present invention is to provide a sheet calipering mechanism of novel construction and operation for preventing the simultaneous feeding of more than one sheet to a printing press or other sheet fed machine.

Another object is to provide a novel sheet calipering mechanism which is effective at a certain time in each feeding cycle and for a portion only of said cycle to caliper the sheets, and so constructed to enable the use of simple and inexpensive operating and control means therefor.

Another object is to provide a novel sheet calipering mechanism wherein the calipering operation is effected by a rotary member which is normally disposed out of sheet calipering position and so operated and controlled that it makes a portion of a revolution only during each feeding cycle to caliper the sheets, and at a surface speed substantially equal to the surface speed of the sheets to be calipered.

A further object is to provide a novel sheet calipering mechanism having an intermittently operated rotary sheet calipering member formed with a plurality of circumferentially spaced sheet engaging surfaces whereby a plurality of sheets may be successively calipered in one full revolution of said member.

The above and further objects and novel features of the present invention will more fully appear from the following detail description when the same is read in connection with the accompanying drawings. It is to be expressly understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

2

Fig. 1 is a vertical longitudinal sectional view of a stream feeder, looking toward one side thereof, and showing sheet calipering mechanism constructed in accordance with the present invention;

Fig. 2 is a top plan view of the portion of the feeder shown in Fig. 1, and including part of the driving means for the sheet calipering mechanism;

Fig. 3 is a vertical longitudinal sectional view of the sheet feeder looking toward the opposite side thereof and showing operating means for the sheet calipering mechanism;

Fig. 4 is a top plan view of the portion of the feeder shown in Fig. 3;

Fig. 5 is an enlarged fragmentary side elevation, partly in section, of the sheet calipering mechanism shown in Figs. 1 and 2;

Fig. 6 is a vertical transverse sectional view of the sheet calipering mechanism shown in Fig. 5;

Fig. 7 is a sectional view on the line 7—7 of Fig. 6;

Fig. 8 is an enlarged fragmentary side elevation, partly in section, of the operating means for the sheet calipering mechanism; and

Fig. 9 is a top plan view of the operating means shown in Fig. 8.

Referring to the drawings, 10 indicates part of the frame of a stream feeder which includes

30 a pile elevator comprising a pile board 11 adapted to support a pile of sheets 12 (Figs. 1 to 4). Pile board 11 and pile of sheets 12 are raised intermittently in the usual manner to keep the top of said pile at a predetermined level as the sheets 35 are fed in succession therefrom. The sheets are separated and forwarded one after another from the top of pile 12 in a manner well understood in the art by sheet separating and forwarding devices (not shown), and delivered under and in 40 lapped relation to conveying means driven continuously at slow speed to enable lapping of the sheets thereon. The conveying means comprising a feed roller 13 and pressure rollers 14 cooperating with said feed roller to receive the forwarded sheets in lapped relation and advance said sheets to slow moving tapes 15 that convey a stream of the lapped sheets along a feed board 16 to a printing press or other machine with which the feeder is associated. The rear ends of tapes 15 pass around and are driven by a roller 17, and the front ends of said tapes pass around an idler roller 18 located at the front of feed board 16 and journaled thereon in any suitable manner. Rollers 13 and 17 are journaled on frame 10, and 50 said rollers and tapes 15 are driven continuously 55

by any suitable means and in a manner well understood in the art such that the sheets will be advanced along feed board 16 a part only of the distance between the feeder and press or other machine for each cycle of operation of the feeder. Pressure rollers 14 are journaled on arms 19 adjustably secured on a transverse shaft 20 fixed at its opposite ends in frame 10. Feed board 16 is supported at its rear end by tape roller 17, and at its front end by two posts 21 projecting inwardly from and secured to side rails 22 forming extensions of frame 10.

The stream of lapped sheets is advanced along feed board 16 with the leading sheet uppermost, and as each sheet arrives at the forward end of said feed board and in proximity to the printing press, indicated generally at 23, it is front registered against front stops 24 (Figs. 1 to 4). The latter are operated in synchronism with the feed of the sheets and the action of the press, as well understood in the art, so as to be engaged by the leading edge of each sheet upon its arrival at the forward end of the conveyor. Stops 24 are carried on a rock shaft 25 and preferably swing up and down through slots formed on the forward edge of a plate 26 secured at its opposite ends to blocks 27 which, in turn, are bolted to rails 22. After the sheet is front registered by stops 24, said sheet is side registered by a side registering device (not shown) in a manner well understood in the art, whereupon stops 24 are moved downwardly and the registered sheet is gripped along its front edge by grippers 28 mounted on an oscillating transfer mechanism 29 of the printing press and taken into the press for performance of the printing operations thereon in the usual manner.

Novel mechanism is provided for caliperizing each leading sheet of the stream during movement of the same toward the stops 24 and prior to engagement of the front edge thereof with said stops, and for effecting stopping of the feeder and tripping of the printing press in the event more than a single sheet or sheet thickness is present at the caliperizing point and at the time of the caliperizing operation. As herein shown, said sheet caliperizing mechanism, indicated generally at 38, is preferably constructed, mounted and operated as follows.

Arranged adjacent the front end of the conveyor, between tape roller 18 and plate 26, are two longitudinally spaced cross bars 31 bolted at their opposite ends to blocks 27 (Figs. 1 to 4). The sheets are guided over bars 31 by transversely spaced tongues (not shown) adjustably secured to the underside of feed board 16 and extending therefrom over tape roller 18 and bars 31 to plate 26. Resting on the tops of bars 31 is a bracket 32 (Figs. 5, 6 and 7) having a portion 33 projecting downwardly between said bars, and an upwardly projecting portion 34. Bracket 32 and parts carried thereby hereinafter described may be adjusted laterally of the conveyor along bars 31 in accordance with variations in width of the sheets handled in the feeder, and may be secured in any desired position of adjustment by a clamp screw 35 (Fig. 6). The latter extends loosely through bracket 32 and has threaded engagement in a suitable opening in a clamp block 36 engaged with the undersides of bars 31. Upon rotation of screw 35 in the proper direction, bracket 32 may be released from or clamped to bars 31 for adjustment and clamping purposes relative thereto.

Disposed between bars 31, and preferably beneath the path of travel of the sheets, is a rotary sheet caliperizing member 37 (Figs. 5 and 6). This

sheet caliperizing member 37 is preferably in the form of a roller undercut in its periphery at three equally spaced points, as indicated at 38 (Fig. 5), to provide three equally spaced, abbreviated sheet engaging surfaces 39 preferably curved concentric with the axis of rotation thereof. Caliperizing member 37 is journaled on a ball bearing 40 (Fig. 6) having its outer race secured by a press fit in said caliperizing member, and its inner race secured by a press fit on the reduced end 41 of a bushing 42 which, in turn, is secured by a press fit in a suitable opening formed in the lower portion 33 of bracket 32. Caliperizing member 37, through the described mounting therefor, will thus move with bracket 32 when the latter is adjusted along bars 31 for different widths of sheets. Due to the formation of caliperizing member 37 as described, only the surfaces 39 thereof will engage the sheets, while the undercut portions 38 of said member will present no interference to the forwardly moving sheets.

The sheet caliperizing member 37 is normally disposed with an undercut portion 38 thereof in sheet caliperizing position as shown in Fig. 5, and is operated at a predetermined time during each cycle of operation of the feeder, and in a manner such that it is rotated only a third of a revolution of 120° during each cycle and substantially at the same surface speed as the surface speed of forward travel of the sheets to move the following sheet engaging surface 39 through sheet caliperizing position and at sheet speed, and to dispose the next following undercut portion 38 in sheet caliperizing position. As herein shown, said operation of the sheet caliperizing member 37 is preferably accomplished in the following manner and by the following instrumentalities.

Disposed within the hub 43 of caliperizing member 37 is a driving disc 44 (Fig. 6) having secured therein a laterally projecting crank pin 45 which extends through an opening formed in a circular plate 46. The latter is secured, as by bolts 47, to the end of hub 43 to rotate caliperizing member 37 when disc 44 is rotated as hereinafter described. Plate 46 also serves to maintain disc 44 in driving relation with caliperizing member 37 in all positions of lateral adjustment of said member and bracket 32. Disc 44 is mounted for sliding movement on a transverse shaft 48 and is connected with the latter for rotation thereby, by a key 49 secured in said disc and slidably engaged in a keyway 50 formed in and extending longitudinally of said shaft. Shaft 48 extends approximately half the width of the conveyor through the bushing 42 and plate 46, and is journaled at its opposite ends in suitable bearings in brackets 51 and 52 (Figs. 1 and 2) bolted to the undersides of bars 31.

Fixed on the end of shaft 48 adjacent bracket 52 is a spur gear 53 (Fig. 2) which meshes with a slightly larger spur gear 54. The latter is fixed on a transverse shaft 55 having one end journaled in a suitable bearing in bracket 52 and extending therefrom to the opposite side of the conveyor and journaled at said side in a suitable bearing in a bracket 56 (Figs. 3, 4, 8 and 9) bolted to the undersides of bars 31. Shaft 55 has fixed thereon adjacent bracket 56 a spur pinion 57 (Figs. 8 and 9) which meshes with a spur gear 58 journaled on a stud 59 secured in bracket 56. Mounted for oscillating movement on the hub 60 of gear 58 is a pawl carrier 61 having fixed therein a pin 62 projecting laterally from opposite sides thereof. Pivoted on pin 62 at one side of pawl carrier 61 is a pawl 63 adapted to engage the

teeth of a ratchet 64 secured in any suitable manner on hub 60 of gear 58. Pawl 63 is yieldingly held in continuous engagement with ratchet 64 by a torsion spring 65 surrounding pin 62 and having one end connected with said pawl and the opposite end connected with an adjusting nut 66 carried by said pin.

Pivoted on pin 62 at the opposite side of pawl carrier 61 is one extremity of a connecting link 67 (Figs. 3 and 4) the opposite extremity of which is pivotally connected at 68 with a lever 69 pivoted at 70 on the adjacent rail 22. Pivotally connected with lever 69 at 71 is one end of a connecting rod 72 that extends from said lever rearwardly of the conveyor and has its opposite end pivotally connected at 73 with an arm 74 fixed on a transverse shaft 75 journalled in suitable bearings in frame 10. Fixed on shaft 75 is a lever 76 having pivotally connected therewith at 77 one end of a cam strap 78 that extends rearwardly above and below a transverse cam shaft 79 and has journalled on the opposite end thereof a roller 80. The latter extends into a cam groove 81 formed in a box cam 82 secured to shaft 79 which is journalled in suitable bearings in frame 10 and is driven by any suitable source of power, as, for example, the printing press, to make one complete revolution for each cycle of operation of the feeder.

The sheet caliper member 37, through the described driving connections therefor with ratchet 64, and through the described operating connections for said ratchet with cam 82, will thus be intermittently actuated and once only during each cycle of operation of the feeder, said cam and said connections being so proportioned that caliper member 37 at each actuation thereof will be rotated a third of a revolution or 120° and at substantially the same surface speed of rotation as the feed roller 13 and tape roller 17, to bring a sheet engaging surface 39 into and out of sheet caliper position at substantially the same surface speed as the surface speed of forward travel of the sheets. Ratchet 64 is held in operated position and against return rotation as pawl carrier 61 is returned for pawl 63 to engage with the next tooth on said ratchet by a roller 83 (Figs. 8 and 9) engaged with the ratchet between two teeth thereon and journalled on a spring pressed bell crank 84 loosely mounted on a stud 85 secured in and projecting laterally from bracket 56. The spring for bell crank 84 is indicated at 86 and is mounted on a rod 87 having one end pivotally connected with said bell crank and the opposite end guided in a suitable opening formed in a stud 88 secured in bracket 56.

Cooperating with the sheet caliper member 37 and preferably disposed above the path of travel of the sheets, is a normally stationary caliper element 89 (Figs. 5 and 6). This caliper element 89 may be of any suitable form and as herein shown is preferably in the form of a segment secured in any suitable manner to a pin 90 journalled in a suitable bearing in a lever 91 and projecting outwardly through opposite sides of said lever. Lever 91 is carried by bracket 32 for lateral adjustment therewith, and for this and other purposes said lever is pivotally mounted on a stud 92 secured in the upper portion 34 of said bracket. Segment 89 is normally disposed in the position thereof shown in Fig. 5, and engaged with a pin 93 by a light pull spring 94 having one end connected with said pin and the opposite end connected at 95 with said segment. Pin

93 is secured in and projects laterally from lever 91.

Threaded through a suitable opening in a vertical extension 96 of lever 91 is an adjusting screw 97 (Fig. 5) engaging one side of a stud 98 secured in the upper portion 34 of bracket 32. Screw 97 is held in engagement with stud 98 by a push spring 99 engaging the opposite side of stud 98 and carried in a suitable socket formed in a vertical extension 100 of lever 91. Rotation of screw 97 in opposite directions will cause lever 91 to move clockwise and counter-clockwise about its pivot 92, thereby lowering and raising caliper segment 89 which is so regulated that space equal to the thickness of a single sheet will be left between said segment and the caliper member 37 when the sheet engaging surfaces 39 of the latter are rotated into sheet caliper position. Screw 97 is held in adjusted positions by a lock nut 101.

Secured in any suitable manner to pin 90 adjacent the end thereof opposite that carrying segment 89 is a segmental-shaped finger 102, and loosely mounted on said pin adjacent said finger is a pendulum or abutment 103 formed with an arcuate surface 104 slightly eccentric with respect to the axis of rotation of said pendulum (Figs. 5, 6 and 7). Pendulum 103 is connected with finger 102 by a yielding connection in the form of a light pull spring 105 having one end connected with a pin 106 secured in said pendulum, and the opposite end connected with a pin 107 secured in said finger. Pin 106 is normally maintained in engagement with finger 102 by spring 105 so as to hold pendulum 103 in the full line position thereof shown in Fig. 7, and enable movement past the same of raising and lowering sheet feeder and printing press control means.

As herein shown said sheet feeder and printing press control means comprise a feeler or detent preferably in the form of a rod 108 (Figs. 5, 6 and 7) guided for vertical reciprocation toward and away from pendulum 103 in a suitable opening in the lower portion 33 of bracket 32 and pivotally connected at its lower end with an arm 109. The latter is keyed to a transverse rock shaft 110 provided with a longitudinally extending keyway 111 to enable lateral adjustment of arm 109 with bracket 32 without disturbing the connection for said arm with said shaft. Accordingly, the lower portion 33 of bracket 32 has bolted to one side thereof an angle plate 112 extending laterally therefrom beyond arm 109 and forwardly in front of said arm. Shaft 110 extends through the lower portion 33 of bracket 32 and is journalled at its opposite ends in suitable bearings in brackets 51 and 52 (Fig. 2). Rocking motion of shaft 110, imparted thereto as presently described, results in rocking motion of arm 109 and up and down movement of feeler 108.

Shaft 110 is rocked by suitable mechanism which, as herein shown, comprises an arm 113 (Figs. 1, 2, 5 and 6) fixed on the end of said shaft adjacent bracket 51, and having pivotally connected therewith at 114 one end of a connecting rod 115. The latter extends rearwardly of the conveyor and has its opposite end pivotally connected at 116 with the arm 117 of a double-armed lever 118 the other arm of which is indicated at 119 (Figs. 1 and 2). Lever 118 is fixed on a shaft 120 journalled in a suitable bearing in the adjacent side rail 22. Pivotally connected at 121 with arm 119 of lever 118 is one end of a connecting rod 122 the opposite end of which is pivotally connected at 123 with the arm 124 of a double arm

lever 125 the other arm of which is indicated at 126. Lever 125 is pivotally mounted at 127 on the adjacent frame 10. Pivotally connected at 128 with arm 126 of lever 125 is one end of a cam strap 129 which extends rearwardly above and below cam shaft 79 and has journalled on the opposite end thereof a roller 130 engaged with a cam 131 fixed on said shaft. Roller 130 is biased toward cam 131 by a spring pressed rod 132 having one end pivotally connected at 133 with the arm 126 of lever 125, and the opposite end guided in a suitable opening formed in a stud 134 secured to the adjacent frame member 10. The spring 135 for rod 132 is mounted thereon between stud 134 and a collar 136 adjustably secured to said rod. Feeler 108 will thus be raised by spring 135 and lowered by cam 131 once during each cycle of operation of the feeder, said raising movement of feeler 108 being so timed with respect to the rotation of caliper member 37 that it occurs after said caliper member has rotated a third of a revolution. Further, when feeler 108 is raised and lowered as aforesaid, rocking motion will be imparted by lever 118 to shaft 120 which is connected with well-known mechanism (not shown) for stopping the feeder and tripping the printing press in the event rocking movement of said shaft is interrupted as herein-after described.

Since the sheet caliper mechanism 30 is arranged for operation at the front of the conveyor and on sheets that are fed in lapped relation, there will be at certain times more than a single sheet present between the caliper member 37 and segment 89 as, for example, when a sheet is being carried into the press by grippers 28 and a succeeding sheet is approaching the front stops 24. The timing of the feeder, press, and sheet caliper mechanism is such, however, that the sheet caliper member 37 is rotated only when one sheet should normally be present for the caliper operation.

Assuming now that the tail of the sheet being carried into press has passed the sheet caliper position, and that the leading edge of a succeeding sheet has moved slightly beyond sheet caliper position, the caliper member 37 is then rotated a third of a revolution or 120° by the described operating mechanism therefor, and substantially at the same surface speed as the surface speed of forward travel of the sheet, whereupon the following sheet engaging surface 39 of said member is moved at sheet speed through and beyond the sheet caliper position and the next following undercut portion 38 of member 37 is moved into position beneath segment 89. Upon rotation of caliper member 37 as aforesaid, the sheet is engaged by the surface 39 of said member and lifted slightly toward the segment 89.

If, during rotation of caliper member 37, and upon engagement of surface 39 with the sheet, there is no additional sheet or sheet thickness present, the segment 89 and the pendulum 103 will remain stationary in the positions thereof shown in Figs. 5 and 6. In such event, the feeler 108 is permitted to move upwardly past pendulum 103 as indicated in broken lines in Fig. 7, accompanied by rocking movement of shaft 120, and normal feeding, conveying and printing of the sheets in succession thus proceeds without interruption.

Assuming now that two sheets are moving toward stops 24 at a time when normally one sheet only should be present for the caliper operation. In this event, and with an extra sheet

thickness at the caliper position, the segment 89 will, upon rotation of caliper member 37 and engagement of surface 39 thereof with the double or excess sheet thickness, be rotated clockwise as viewed in Fig. 5, through frictional contact of the forwardly moving sheets therewith. Rotation of segment 89 causes pin 90 to rotate finger 102 clockwise and thus swing pendulum 103 through spring 105 in the same direction, whereupon the eccentric arcuate surface 104 of said pendulum will move downwardly toward feeler 108 until it engages and is wedged against the upper end of said feeler as indicated in broken lines in Fig. 7. Feeler 108 will thus be prevented through such engagement from moving upwardly, and consequently, roller 130 cannot follow the low part of cam 131 to rock shaft 120. Failure of shaft 120 to rock results in actuation of the feeder stopping and press tripping mechanisms (not shown) which are connected with said shaft, and stopping of the feeder and tripping of the press. When the arcuate surface 104 of pendulum 103 engages feeler 108, further rotation of said pendulum is prevented, the segment 89 and finger 102, however, will continue to rotate due to the spring connection 105 between said pendulum and said finger, until the surface 39 of caliper member 37 has rotated beyond sheet caliper position. Caliper segment 89 when once actuated is held in actuated position to prevent resetting of the same and the pendulum 103 until the feeder has been stopped and the press has been tripped. For this purpose, lever 91 has pivotally mounted thereon at 137 an overbalanced pawl or latch 138 (Fig. 5) adapted, when segment 89 is rotated, to automatically engage in one or the other of two teeth 139 formed in the periphery of said segment.

Upon stopping of the feeder and tripping of the printing press, the leading sheet and the excess sheet or sheets are removed from the conveyor, thereupon pawl 138 is manually disengaged from segment 89, and the latter, the finger 102, and the pendulum 103 are returned to their original positions shown in Fig. 5 by the contracting action of springs 94 and 105, and fully reset for the next operation. The feeder and printing press are then again started by suitable means for this purpose, and the feeding, conveying, caliper, registering and printing operations proceed normally in connection with successive sheets of the stream.

Lever 91 is provided with a handle 140 so that said lever may be manually swung clockwise (Fig. 5) about its pivotal axis, and thereby raise segment 89 and pendulum 103 to enable removal of the excess sheet or sheets from the conveyor, and resetting of said segment and pendulum, in the event the feeder upon actuation of the caliper mechanism, should, for some reason, stop only after the next following surface 39 of caliper member 37 has moved into caliper position, or when feeler 108 is applying an upward thrust against pendulum 103. The eccentric arcuate surface 104 of pendulum 103 eliminates all upward lost motion of feeler 108 in all positions of vertical adjustment of segment 89 relative to caliper member 37 for sheets of various thicknesses handled in the feeder. When pendulum 103 is rotated into the path of upward movement of feeler 108, the arcuate surface 104 of said pendulum will gradually move downwardly toward said feeler until the pendulum is stopped by the latter as hereinbefore described.

There is thus provided a sheet caliper mechanism

anism wherein caliper of successive forwardly moving sheets is effected by a rotary caliper member having a plurality of equally spaced sheet engaging surfaces on the periphery thereof which are normally disposed out of caliper position and rotated one after another into caliper position at predetermined intervals to caliper the successive sheets. This has the advantage in that it enables provision of a caliper mechanism wherein none of the parts thereof are in motion during a major portion of each feeding cycle, and certain of said parts only are in motion for a small fraction of each feeding cycle, thereby materially decreasing wear of said mechanism with the result that accurate caliper of sheets is assured for an indefinite period. Additionally, the intermittent and partial rotation of the sheet caliper member simplifies the construction and operation of the sheet caliper mechanism and enables the use of simple and inexpensive driving and control means therefor.

While the present invention is herein described and illustrated in connection with sheets that are advanced in lapped relation toward a printing press or other sheet fed machine, it is equally adaptable for embodiment in sheet feeders wherein the sheets are advanced singly one after another in spaced relation to a printing press or other machine, or in the combination type of sheet feeder which is capable of feeding the sheets either in lapped relation or in spaced relation.

Further, the sheet caliper mechanism herein illustrated and described may be arranged for operation at any desired point on the conveyor between the front and rear ends thereof, and is capable of operation on plural sheets, as for example, a predetermined number of lapped sheets, as distinguished from a single sheet.

It is therefore to be expressly understood that the term "predetermined number" as hereinafter employed is intended to apply to a single sheet or sheet thickness as well as plural sheets or a plural sheet thickness, and that the present invention is not limited to the embodiment or location thereof herein illustrated and described or otherwise than by the terms of the appended claims.

What is claimed is:

1. In a sheet feeder for feeding sheets toward a machine to be fed, means for caliper the sheets during forward movement thereof comprising a rotary sheet caliper member having a plurality of sheet engaging surfaces equally spaced about the periphery thereof and normally disposed out of sheet caliper position, means for intermittently rotating said sheet caliper member to move the sheet engaging surfaces thereof successively through sheet caliper position and into engagement with successive sheets, and means responsive to the rotation of said sheet caliper member for interrupting the feed of sheets when more than a predetermined number of sheets at a time is present at the sheet caliper position and engaged by any one of said sheet engaging surfaces.

2. In apparatus of the character described having means for advancing sheets in succession toward a machine to be fed, means for caliper the successive sheets during advancing movement thereof comprising a rotary sheet caliper member having a plurality of sheet engaging surfaces equally spaced about the periphery thereof and normally disposed out of sheet cal-

iper position, means for rotating said sheet caliper member intermittently and at a speed substantially equal to the surface speed of the advancing sheets whereby the sheet engaging surfaces thereof are moved successively through sheet caliper position and into engagement with successive sheets at sheet speed, and means responsive to the rotation of said sheet caliper member for interrupting the advance of the sheets when more than a predetermined number of sheets is present at the sheet caliper position and engaged by any one of said sheet engaging surfaces.

3. In sheet feeding apparatus for feeding sheets one after another in timed relation toward a machine to be fed, means for caliper the successive sheets during forward movement thereof comprising a rotary sheet caliper member having a sheet engaging surface normally disposed out of sheet caliper position, means for rotating said sheet caliper member at a predetermined interval a portion of a revolution only to move the sheet engaging surface thereof through sheet caliper position and into engagement with a sheet, and means controlled by said sheet caliper member for interrupting the feed of sheets when more than a predetermined number of sheets at a time is present at the sheet caliper position and engaged by said sheet engaging surface.

4. In apparatus of the character described having means for advancing sheets one after another in timed relation toward a machine to be fed, means for caliper the successive sheets during advancing movement thereof comprising a rotary sheet caliper member having a plurality of sheet engaging surfaces equally spaced about the periphery thereof and normally disposed out of sheet caliper position, means for rotating said sheet caliper member at predetermined intervals a portion of a revolution only and at a speed substantially equal to the surface speed of the advancing sheets whereby the sheet engaging surfaces thereof are moved successively through sheet caliper position and into engagement with successive sheets at sheet speed, and means controlled by said sheet caliper member for interrupting the feed of sheets when more than a predetermined number of sheets at a time is present at the sheet caliper position and engaged by any one of said sheet engaging surfaces.

5. In a sheet caliper mechanism for sheet feeders, a normally stationary caliper element, a normally stationary rotary sheet caliper member spaced from and cooperating with said caliper element to effect actuation thereof only in the event more than a predetermined number of sheets at a time is passed between the same and said sheet caliper member, said sheet caliper member having a plurality of sheet engaging surfaces equally spaced about the periphery thereof and normally disposed out of sheet caliper position, and means for rotating said sheet caliper member at predetermined intervals a portion of a revolution only to move one only of the sheet engaging surfaces thereof through sheet caliper position upon each actuation of said member.

6. In mechanism of the character described, a normally stationary caliper element, a normally stationary rotary sheet caliper member spaced from and cooperating with said caliper element to effect actuation thereof only in the event more than a predetermined number of sheets at a time is passed between the same and said sheet caliper-

11

ing member, said sheet caliper member having a plurality of sheet engaging surfaces equally spaced about the periphery thereof and normally disposed out of sheet caliper position, and means for rotating said sheet caliper member at predetermined intervals a portion of a revolution only and at a speed substantially equal to the surface speed of the passing sheets whereby one only of the sheet engaging surfaces thereof is moved through sheet caliper position and substantially at sheet speed upon each operation of said member.

7. In a sheet caliper mechanism for sheet feeders, a normally stationary caliper element, a rotary sheet caliper member spaced from and cooperating with said caliper element to effect actuation thereof in the event more than a predetermined number of sheets at a time is passed between the same and said sheet caliper member, said sheet caliper member having a plurality of sheet engaging surfaces equally spaced about the periphery thereof and normally disposed out of sheet caliper position, and means including a pawl and ratchet for rotating said sheet caliper member at predetermined intervals a portion of a revolution only and at a speed substantially equal to the surface speed of the passing sheets whereby one only of the sheet engaging surfaces thereof is moved through sheet caliper position and at sheet speed for each feeding cycle.

8. A sheet caliper mechanism for sheet feeders, comprising a normally stationary caliper element, a normally stationary rotary sheet caliper member spaced from and cooperating with said caliper element to effect actuation thereof only in the event more than a predetermined number of sheets at a time is passed between the same and said sheet caliper member, said sheet caliper member having three sheet engaging surfaces equally spaced about the periphery thereof and normally disposed out of sheet caliper position, and means for rotating said sheet caliper member at predetermined intervals a third of a revolution only and at a speed substantially equal to the surface speed of the passing sheets whereby one only of the sheet engaging surfaces thereof is moved through sheet caliper position and at sheet speed for each feeding cycle.

9. In mechanism of the character described, a normally stationary pivotally mounted caliper segment provided with at least one tooth in the periphery thereof, a driven member spaced from and cooperating with said segment to effect rotation of the latter in the event more than a predetermined number of sheets at a time is passed between the same and said driven member, and a pawl movable into engagement with said tooth upon rotation of said segment to hold the latter in actuated position.

10. In combination, a normally stationary rotatably mounted caliper element, a driven mem-

12

ber spaced from and cooperating with said caliper element to effect rotation thereof in the event more than a predetermined number of sheets at a time is passed between the same and said driven member, a raising and lowering sheet feeding control member, means for controlling the actuation of said sheet feeding control member comprising a rotatable element having an arcuate surface eccentric with the axis of rotation thereof and normally removed from the path of movement of the sheet feeding control member, and means connecting said last named element with said caliper element for rotation by the latter to dispose the arcuate surface thereof into the path of movement of the sheet feeding control member and thereby stop raising movement thereof.

11. In apparatus of the class described for feeding sheets one after another in timed relation toward a machine to be fed, a sheet caliper member having normally stationary sheet engaging surfaces spaced apart the periphery thereof and movable one after another into engagement with successive sheets, means operable in timed relation with the feed of the sheets for imparting a rotary step-by-step movement to said member to move the sheet engaging surfaces thereof successively into sheet caliper position, and a normally stationary caliper element actuated by said member only when an undesired number of sheets at a time is passed between said member and said element.

12. In apparatus of the class described, a sheet caliper member having sheet engaging surfaces on the periphery thereof, means for imparting a rotary step-by-step movement to said member, a caliper element actuated by said member when an undesired number of sheets at one time is passed between said member and element, a controlling member, means yieldingly connecting said controlling member to said element, and a feeler adapted to engage said controlling member when said undesired number of sheets is passed between said caliper member and element.
